LIGHT FOR BICYCLE SAFETY STAFF

Mike C. Blume, P.O. Box 1125,
Kissimmee, Fla. 32741

Filed July 10, 1974, Ser. No. 487,247

Term of patent 3½ years

Int. Cl. D10—06; D26—02
U.S. Cl. D10—111

FIG. 1

FIG. 2

FIG. 3

FIG. 4

FIG. 1 is a side perspective view of a light for bicycle safety staff showing my new design;

FIG. 2 is a side view thereof on an enlarged scale;

FIGS. 3 and 4 are respectively top and bottom plan views on a greatly enlarged scale.

I claim:

The ornamental design for a light for a bicycle safety staff, as shown and described.
